ATTORNEY

UNITED STATES PATENT OFFICE.

WILLIAM F. TURMAN, OF WEATHERFORD, TEXAS.

TRACE ATTACHMENT.

SPECIFICATION forming part of Letters Patent No. 415,928, dated November 26, 1889.

Application filed March 19, 1889. Serial No. 303,874. (No model.)

To all whom it may concern:

Be it known that I, WILLIAM F. TURMAN, of Weatherford, in the county of Parker and State of Texas, have invented a new and useful Improvement in Trace Attachments, of which the following is a full, clear, and exact description.

My invention relates to an improvement in couplings for tug-straps, and has for its object to provide a simple, economical, and durable device, capable of convenient manipulation, and whereby the tug-strap may be expeditiously attached to the cockeye of the whiffletree or detached therefrom.

15 The invention consists in the novel construction and combination of the several parts, as will be hereinafter more fully set forth, and pointed out in the claims.

Reference is to be had to the accompanying drawings, forming a part of this specification, in which similar figures and letters of reference indicate corresponding parts in all the views.

Figure 1 is a plan view of the device attached 25 to a tug-strap. Fig. 2 is a longitudinal section on line $x-x$ of Fig. 1. Fig. 3 is a partial longitudinal or transverse section taken on line $y-y$ of Fig. 1. Fig. 4 is a bottom plan view of the sliding cover-plate, and Fig. 5 is 30 a plan view of the body of the device with the cover-plate removed therefrom.

In carrying out the invention the body 10 of the device is secured in any approved manner to one end of the tug-strap 11. The body 35 10 consists of a suitable block of metal provided with a recess 12 in its upper face open at the forward end, as shown at 13 in Fig. 5, the side and rear walls of which recess are preferably undercut. In the base-wall of the 40 recess, near one side, two slots 14 and 15 are produced, and in the under face of the body a longitudinal groove 16 is formed, extending parallel with the edge from the outer end over a metal bridge 17, dividing the two slots 45 14 and 15. In the groove 16 a locking-plate 18 is located, which plate has vertical movement in the outer portion of the said groove and extends beyond the rear or outer end of the body, as shown in Fig. 3. This locking- 50 plate 18 is provided upon the under side near the outer extremity with a pin 19, and upon the upper face of the plate two latch-heads

20 and 21 are longitudinally produced, the inner head 20 being the larger of the two. Both of the latch-heads are curved upon the 55 inner face and are provided with a perpendicular outer face, as best shown at a .

Prior to the body 10 being secured upon the tug-strap 11 a slight groove is preferably made in the contacting face of the strap to 60 receive the outer portion of the locking-plate 18, whereby the said locking-plate may have free vertical movement while the inner end of the same is held essentially stationary, as best illustrated in Fig. 3, and in the said 65 groove or channel of the tug-strap receiving the locking-plate a recess 22 is formed, adapted to receive a spiral, coil, or other form of spring 23, through which spiral or coil spring the pin 19 of the locking-plate passes, 70 whereby the outer end of the plate is normally held in contact with the under surface of the body and is prevented from being drawn outward therefrom.

Near the end of the body, and about centrally within the recess 12 thereof, an opening 24 is cut, as shown in Figs. 2 and 5, and an aligning and preferably a smaller opening 26 is formed in the tug-strap, whereby the cockeye 27 of the whiffletree 28 may be 80 projected from the rear of the tug-strap into the recess of the body, as shown in Fig. 2.

A cap-plate 29 is held to slide in the recess of the body and cover the same, which cap-plate is provided with a lip 30, projected from 85 the top thereof, as best shown in Fig. 4, adapted to slide over the end of the body 10 when the cap-plate is in a locked position. In the center of the cap-plate at the outer end an undercut recess 31 is formed, which recess is widest at 90 the outer end, and at this point the walls of the recess are preferably circular, as illustrated at 32 in said Fig. 4. The inner portion of the recess is preferably rectangular, as illustrated at 33 in the same figure. 95 The under side of the cap-plate between the rectangular portion of the recess 31 and the side is provided with a groove or channel 34 parallel with the side, and a transverse channel is produced between the rear end of the 100 groove or channel 34 and the outer end of the cap-plate to form a latch-head 35. When the cap-plate is slid to a locked position upon the body-plate 10, the latch-head 35 of the cap-

plate engages with the smaller latch-head 21 of the locking-plate 18, and the inner latch-head 20 of the said locking-plate projects upward within the channel 34 of the cap-plate, as illustrated in Fig. 3.

In operation, when the parts are in the position illustrated in Fig. 3, the cockeye extends inward until the head thereof is within the undercut recess 31, as shown in Fig. 2, and 10 the shank is held within the rectangular portion of the said undercut recess. To release the tug-strap from the cockeye the outer end of the locking-plate is depressed, which disengages the latch-head 21 from the latch-head 35 of the cover-plate. Said cover-plate may now be slid to the rear, the rearward movement being limited by the contact of the rear wall of the channel 34 with the perpendicular face of the inner latch-head 20 of 15 the locking-plate. When the parts are in this position, the enlarged outer end of the undercut recess 31 is made to register with the opening 24 and the opening 26 in the tug-strap. Thus the openings from the wall of 20 the undercut recess in the cap-plate outward are of sufficient size to permit of the device and strap being readily and expeditiously detached from the cockeye.

In attaching the strap to the cockeye when 25 the cover is in the open position just described, the cockeye is passed in through the opening in the tug-strap and registering-opening 24 in the body, and into the undercut recess 31 of the cover-plate through the enlarged portion thereof. The spring 23 causes the outer end of the locking-plate to constantly engage with the under surface of the cover-plate. Thus as the cover-plate is closed the latch-head 35 thereof engages again with 30 the latch-head 21 of the locking-plate and the head of the cockeye is brought within the under-cut of the recess 31. The shank extends outward through the rectangular portion of the recess, thus rendering it impossible for the tug-strap to be detached until the 35 cover-plate is again opened.

It will be observed that should the cockeye become at any time separated from the whiffletree it will remain within the coupling, and may be readily secured for replacement.

I desire it to be distinctly understood that while specific construction has been shown

and described I do not confine myself thereto, as other equivalent construction may be employed without departing from the spirit of the invention.

Having thus described my invention, I claim as new and desire to secure by Letters Patent—

1. In a trace attachment, the combination, 60 with a body-plate having an undercut recess in its outer face open at one end, two spaced longitudinal slots formed in the base-wall of the recess near one side, and an opening near the end wall of the said recess, of a spring-actuated locking-plate extending outward from the body in contact with its under face and provided with latch-heads projected upward through the said longitudinal slots, a cover-plate held to slide upon the body, having 65 a longitudinal groove to receive the inner latch-head of the locking-plate, and a latch-head at one end capable of contact with the outer latch-head of the locking-plate, and a central undercut recess at one end, largest at 70 the mouth, all combined for operation substantially as shown and described.

2. In a trace attachment, the combination, 75 with a body-plate having an undercut recess in its outer face, open at one end, two spaced longitudinal slots formed in the base-wall of the recess near one side, and an opening near the end wall of the said recess, of a spring-actuated locking-plate extending outward from the body in contact with its under face, 80 provided with latch-heads having one inclined and one perpendicular face, said latch-heads being capable of projecting through the said longitudinal slots in the body-plate, a cover-plate held to slide upon the body, 85 having a longitudinal groove to receive the inner latch-head of the locking-plate, and a latch-head at one end capable of contact with the outer latch-head of the locking-plate, a central undercut recess at one end, largest at 90 the mouth, and a lip horizontally projected from the upper surface of the latch-head, 95 adapted for engagement with and to slide over the upper surface of the end wall of the body-plate, all combined for operation substantially as shown and described.

WILLIAM F. TURMAN.
